UNITED STATES PATENT OFFICE

DONALD S. SAMMIS, OF STRATFORD, CONNECTICUT, ASSIGNOR TO THE NEW HAVEN SAND BLAST COMPANY, OF NEW HAVEN, CONNECTICUT, A CORPORATION OF CONNECTICUT

SAND BLAST APPARATUS

Application filed October 3, 1929. Serial No. 397,103.

An object of the invention is to provide a sand blast apparatus which will act automatically in a more efficient manner than has been possible in the past. A further object is the provision of an air valve which will control separately and in proper sequence the admission of pressure to, and the passage of air through certain parts of the apparatus. Other objects will later appear.

One form of the invention is shown by the accompanying drawings, wherein—

Figure 1 is an elevation of the apparatus, partly in section,

Fig. 2 is an elevation of part of the apparatus as viewed from the right in Figure 1,

Fig. 3 is a longitudinal section of the valve, and

Fig. 4 is a section through the valve on the line 4—4 of Fig. 3.

The invention contemplates the combination of a novel air valve with a sand bin, a sand tank, a sand bin valve, and other parts, together with connections between the air valve and these parts, the combination functioning in a novel and highly desirable manner.

In the example illustrated, there is shown a sand blast apparatus comprising a sand bin 10, a sand tank 11, and a sand bin valve 12 between the sand bin and the sand tank, all constructed, generally in accordance with known practice. A mixing chamber 13 or pick up chamber, is also shown. There is likewise shown a novel air valve 14, a connection 15 between the air valve 14 and the sand bin valve 12, a separate connection 16 between the air valve and the sand tank 11, and another connection 17 between the air valve and the mixing chamber 13.

The preferred type of air valve is a piston valve, and such a valve is here illustrated and described by way of example. However, I do not desire to be limited to a piston valve.

The air valve 14 here shown comprises a casting formed in two cylinders, a working cylinder 18, and an equalizing cylinder 19. Each cylinder has a pressure end, and an open end which is at all times at atmospheric pressure. Two pistons 20 and 21, respectively, reciprocate in these two cylinders.

The two pistons are connected by a stem 22 and reciprocate together. They are displaced by a lever 23 connected to the stem 22 and swinging over a rack 24. The piston 20 shown on the left in Fig. 3 is the working piston, and the piston 21 shown on the right in Fig. 3 is the equalizing piston. A connection 25 between the opposite ends of the two cylinders 18 and 19 equalizes the pressure in both directions in well-known manner and permits operation of the air valve by means of the lever 23 without the use of undue force.

I may provide plugs 26 in the two cylinders as a means for draining them.

Air under pressure enters the pressure end of the working cylinder 18 through a pipe 27 (and the pressure is, of course, transmitted through the connection 25 to the pressure end of the equalizing cylinder 19). As the working piston is displaced to the right from the position illustrated in Fig. 3, air under pressure is admitted to the connection 15 between the air valve and the sand bin valve, and also to the connection 17 between the air valve and the mixing chamber. At the same time the working piston closes the separate connection 16 between the air valve and the sand tank, which is open to atmosphere when the working piston 20 is in the position shown in Fig. 3. Obviously, if the working piston were moved a sufficient distance to the right it would admit pressure to the connection 16 between the air valve and the sand valve.

By moving the piston in the opposite direction the connection 16 with the sand tank is opened and the connection 15 with the sand bin valve is closed. The piston 20 is thus a means for opening the air connection 16 with the sand tank when the air connection 15 with the sand bin valve is closed. Its action permits escape of air from the sand tank, and opening of the sand bin valve when the supply of air to the sand bin valve is cut off. Whichever way the piston travels one connection is opened and the other closed simultaneously.

The sand bin valve 12 is of well-known construction. It closes by rising until it contacts with a seat 28, and opens by dropping into the sand tank below the seat.

The preferred form of connection between the air valve 14 and the sand bin valve 12 includes a pipe end 29 of the connection 15 which extends upwardly beneath and adjacent to the sand bin valve. A sleeve 30 is attached to the sand bin valve and extends downwardly surrounding the pipe end 29. When the air valve 14 admits pressure through the connection 15 and its pipe end 29 to the sand bin valve 12, this pressure will be communicated to the under side of the sand bin valve inside the sleeve 30, and the sand bin valve will be raised until it contacts against its seat 28. When in the raised position the sand bin valve prevents passage of air out of the sand tank.

From the foregoing description it will be seen that the air valve is adapted to close the sand bin valve by applying pressure thereto, which is accomplished by admitting air to its connection with the sand bin valve.

The sleeve 30 fits closely about the pipe end 29, but does not prevent slight leakage of air into the sand tank 11. This leakage of air permits withdrawal of sand from the sand tank through the mixing chamber 13, as will be subsequently explained.

The separate connection 16 from the air valve to the sand tank 16 gives the sand tank access to the atmosphere when the air valve is closed: that is to say, when the air valve is in the position shown in Fig. 3 of the drawings. As the air valve is opened, the end of the connection 16 is closed by the working piston 20. Air which leaks into the sand tank cannot then escape, but will act to fill the space left by sand which is removed from the sand tank, and to build up pressure in the sand tank thus tending further to lift the sand bin valve against its seat.

When the air valve is closed the connection 15 is closed, the separate connection 16 is opened, and the pressure in the sand tank drops to atmosphere. As the air leaks from between the pipe end 29 and the sleeve 30 the sand bin valve 12 drops into the open position.

From what has been said it will be seen that the air valve is adapted to apply pressure to the separate connections to close the sand bin valve and to operate the mixing chamber. The air valve, by closing the separate connection between the air valve and the sand tank, is adapted to control pressure within the sand tank.

The air valve may also apply pressure within the sand tank separately by means of the separate connection 16 between the air valve and the sand tank. All that is necessary for this purpose is to withdraw the pressure end of the piston 20 beyond the end of the separate connection 16 with the sand tank, as has already been explained.

The mixing chamber 13 is of well-known construction. Air passing therethrough

picks up sand which falls from the sand tank into the mixing chamber carrying the same with high velocity to the point where the sand-blasting operation is to be carried on. Additional pressure within the sand tank 70 will hasten the rate at which sand flows to the mixing chamber. If there is a vacuum in the sand tank, or if no provision is made for air to enter the sand tank to replace the sand passing to the mixing chamber, then the sand 75 will not be able to leave the sand tank and the column of air moving through the mixing chamber 13 will pick up no sand.

It is preferred to form the entrance from the valve into the mixing chamber connection as a slit connection 31 so that the area uncovered as the piston in the valve is moved to the right is proportional to the motion of the piston 20 (see Fig. 4). Thus a slight movement of the piston over the slit 31 admits air into the mixing chamber connection 17 at a slow rate, whereas a greater movement increases the uncovered area of the slit and the rate at which the air is admitted to the mixing chamber. The position of the piston may, therefore, be regulated to cause air to pass through the mixing chamber at the rate desired.

Without limiting myself to the specific form of the invention and details of construction here described and illustrated by way of example,

I claim:

1. In a sand blast apparatus, a sand bin, a sand tank, a sand bin valve between said sand bin and said sand tank, and a mixing chamber operatively associated with said sand tank, in combination with an air valve, a connection between said air valve and said sand bin valve, a separate connection between said air valve and said sand tank, and another connection between said air valve and said mixing chamber, said air valve being adapted to apply air pressure to said sand bin valve connection to close said sand bin valve, while holding pressure within said sand tank by closing said connection between said air valve and said sand tank.

2. In a sand blast apparatus, a sand bin, a sand tank, a sand bin valve between said sand bin and said sand tank, and a mixing chamber operatively associated with said sand tank, in combination with a piston valve, a connection between said piston valve and said sand bin valve, a separate connection between said piston valve and said sand tank, and another connection between said piston valve and said mixing chamber, said piston valve being adapted to apply air pressure to said connections to close said sand bin valve, and to cause air to pass through said mixing chamber while holding pressure within said sand tank.

3. In a sand blast apparatus, a sand bin, a sand tank, a sand bin valve between said

sand bin and said sand tank, and a mixing chamber operatively associated with said sand tank, in combination with an air valve, a connection between said air valve and said sand bin valve, a separate connection between said air valve and said sand tank, and a slit connection between said air valve and said mixing chamber, said air valve being adapted to apply air pressure directly to each of said separate connections to close said sand bin valve, to control pressure within said sand tank, and to cause air to pass through said mixing chamber at the rate desired.

4. In a sand blast apparatus, a sand bin, a sand tank, a sand bin valve between said sand bin and said sand tank, and a mixing chamber operatively associated with said sand tank, in combination with a piston valve, a connection between said piston valve and said sand bin valve, a separate connection between said piston valve and said sand tank, and a slit connection between said piston valve and said mixing chamber, said piston valve being adapted to apply air pressure directly to said separate connections to close said sand bin valve, to control pressure within said sand tank, and to cause air to pass through said mixing chamber, substantially as described.

5. In a sand blast apparatus, a sand bin, a sand tank, and a sand bin valve between said sand bin and said sand tank, in combination with an air valve, comprising a balanced piston valve, a connection between said sand bin valve and said air valve, and a separate connection between said sand tank and said air valve, said piston valve being adapted to open said first-named connection to supply air to close said sand bin valve and close said second-named connection simultaneously to retain pressure in said sand tank.

6. In a sand blast apparatus, a sand bin, a sand tank, a sand bin valve between said sand bin and said sand tank, a mixing chamber, an air valve casing having a balanced piston valve therein and ports in said valve casing having separate connections to said sand tank, sand bin valve and mixing chamber, respectively, said piston valve controlling said ports to vary the supply to said mixing chamber while holding the sand bin valve closed and holding pressure in said sand tank.

In testimony whereof I have signed my name to this specification.

DONALD S. SAMMIS.
